(57) CLAIM

The ornamental design for the pair of shoes, as shown and described.

DESCRIPTION

FIG. 1 is a perspective view of the right shoe of a pair of shoes according to my new design;

FIG. 2 is a right-side view of the shoe of FIG. 1;

FIG. 3 is a left-side view of the shoe of FIG. 1;

FIG. 4 is a top view of the shoe of FIG. 1;

FIG. 5 is a bottom view of the shoe of FIG. 1;

FIG. 6 is a front view of the shoe of FIG. 1; and,

FIG. 7 is a rear view of the shoe of FIG. 1.

The figures depict a right shoe, the left shoe of my design being a mirror image thereof.
